DISHWASHING APPARATUS

Forrest A. Walker, Oak Park, Ill., assignor, by
mesne assignments, to Edison General Electric
Appliance Company, Inc., a corporation of New
York

Application June 22, 1934, Serial No. 731,901

8 Claims. (Cl. 141—9)

This invention relates to dishwashing apparatus, more particularly to apparatus for supporting glassware, dishes and the like, in mechanical dishwashing machines, and it has for 5 its object the provision of improved apparatus of this character.

This invention is particularly applicable to mechanical dishwashing apparatus wherein a cleansing fluid, such as water, is circulated or 10 hurled through the washing vat by suitable power-driven means, such as a motor-driven impeller, so as to effect a washing action on the utensils supported in the vat.

In certain known dishwashing machines of this 15 character, dish-supporting trays are provided formed of open-work wire construction. Usually there are two trays, one located in the lower portion of the vat and the other in the upper portion of the vat immediately above the lower rack. The motor-driven impeller is positioned 20 below the lower rack and is arranged as it revolves to engage cleansing fluid so as to hurl the fluid upwardly and outwardly circumferentially through the racks.

The lower rack is usually arranged to hold platters, large saucers, common dinner plates and the like, while glasses, cups, etc. are placed in the upper rack. The lower rack supports the flat plate-like members in such positions and at 25 such angles that these members not only receive the direct action of the fluid hurled upwardly by the impeller so as to be cleansed, but also act as deflectors or baffles for the water so as to direct the water up into the glasses, cups, etc. placed in the superimposed top tray to effect 30 an efficient cleansing action on these utensils.

Some difficulty has been experienced with this arrangement because oftentimes there are not 35 enough dishes in the bottom tray to deflect and distribute the water properly to the dishes in the upper tray. Moreover, at times, it is desirable to wash glasses and the like in the upper tray when there are no dishes at all in the lower tray to act as deflectors.

It is an object of this invention to provide 40 water distributing members in the vat arranged to deflect or distribute the water that is hurled upwardly by the impeller into the upper tray so that the glassware, etc. placed within the upper 45 tray will be properly washed, irrespective of whether or not there are any flat dishes in a lower tray beneath the upper tray.

In accordance with this invention, in one form 50 thereof, a lower tray is provided formed of open-work wire construction. This tray is provided

with a plurality of vertically arranged metallic baffles arranged to define compartments for receiving flat dishes and the like so as to support these dishes in the proper positions to be cleansed, and in addition, to function as deflectors for 5 directing water hurled upwardly by the impeller into the articles placed within the upper rack.

In another form of this invention, there is provided a suitable supporting framework for the baffles arranged to be fitted in the lower portion of the vat. This framework in this case is not arranged to support dishes within it, as in the first form, but preferably will be arranged to support the upper tray in proper position within the vat. This other form is described and 15 claimed in my copending application, Serial No. 193,909, filed March 4, 1938, and which application is a division of the instant application.

For a more complete understanding of this invention, reference should be had to the accompanying drawings in which Fig. 1 is an elevation of dishwashing apparatus embodying this invention, parts being shown in section and parts being broken away so as to illustrate certain details of construction; Fig. 2 is a fragmentary 20 horizontal sectional view taken on an enlarged scale of a dish-supporting tray used in the apparatus of Fig. 1 and arranged in accordance with this invention; Fig. 3 is a fragmentary vertical sectional view taken through the line 3—3 25 of Fig. 2; Fig. 4 is a view similar to Fig. 1, but illustrating a modified form of this invention; Fig. 5 is a fragmentary plan view of the upper rack used in the washing apparatus of Fig. 4; Fig. 6 is a fragmentary plan view of a part of 30 the apparatus used in the washing apparatus of Fig. 4; and Figs. 7 and 8 are elevation and bottom views of a detergent container used in 35 one form of this invention.

Referring more particularly to Figs. 1 to 3 40 inclusive, this invention has been shown in one form as applied to mechanical dishwashing apparatus comprising a vat and a motor-driven impeller in the lower portion of the vat arranged to circulate cleansing fluid upwardly and 45 outwardly in the vat. As shown, the dishwashing apparatus comprises a vat 10 supported in an upright vertical position by means of a top frame 10a to which it is secured by clamps 10b. The vat 10 has a circular cross-section, but it is 50 to be understood that the vat may have any suitable cross-section, such as a rectangular cross-section.

The vat 10 is provided with an inverted frusto-conical bottom wall 11, preferably formed inte- 55

grally with the side walls of the vat. A suitable removable cover 12 is provided for the vat 10, this cover being provided with a handle 13 whereby it can be conveniently removed and replaced.

5 While the vat together with its bottom wall and cover may be formed of any suitable material, it is preferable to form them from some suitable sheet metal, such as a rust-resistant steel, which preferably will be plated or enameled.

10 Mounted within the conical wall 11 is an impeller 14 arranged when rotated to engage and hurl a cleansing fluid, such as hot water, upwardly and outwardly in the vat with a more or less whirling circumferential motion. The impeller 14 may have any suitable construction, the important feature being that the impeller be given a shape such that the cleansing fluid in the lower portion of the vat will be thrown upwardly and outwardly in an efficient manner by the rotary motion of the impeller. The impeller will be formed of any suitable material, such as cast-aluminum or pressed steel. The impeller 14 is driven by a suitable electric motor 15.

A suitable cleansing fluid, such as hot water, 25 is supplied to the vat by any suitable means, such as by means of a conduit 16 communicating with a fluid supply source and with the vat.

The vat is provided with a suitable drainage outlet (not shown) which is arranged in the bottom wall 11 as close to the bottom of the vat as is practical. This port communicates with a drainage conduit 17. It will be understood that this conduit communicates with a suitable drain valve housing (not shown) in which a suitable drain valve will be provided for controlling the drainage of fluid from the vat. This drain valve housing and valve form no part of this invention and it is believed to be unnecessary, therefore, to describe them in detail.

40 In the vat 10 are a pair of open-work trays or baskets 20 and 21 arranged to receive dishes and the like so as to support them in proper positions to be cleansed by the water which is hurled upwardly and outwardly by the impeller. The rack 20 is placed within the lower portion of the vat directly above the impeller, while the rack 21 is positioned in the upper portion of the vat in superimposed relation with respect to the lower rack 20.

50 It is contemplated that the lower rack will be used to hold platters, dinner plates and other like flat dishes and utensils, whereas the upper rack will be used to support glasses, cups and the like. The upper rack 21, as shown, is arranged to support glasses and the like, indicated in dotted lines in Fig. 1, in an inverted position to receive water which is hurled upwardly and outwardly in the vat so as to be cleansed. The upper rack is supported in the vat by means of a plurality of arms 55 22 which at their upper ends engage the inner surfaces of inclined walls 23 arranged on the top frame 10a.

The lower rack 20 arranged in accordance with this invention is provided with suitable means 65 for engaging the water hurled upwardly by the impeller and deflecting it upwardly in the proper directions through the upper rack 21 so as to effect an efficient cleansing action on the utensils supported within this upper rack.

70 The lower rack, as shown, is formed of a pair of ring-shaped wires 24 and 25 arranged in substantially concentric arrangement (Fig. 2), and being positioned substantially in the same plane, as clearly shown in Fig. 3. Surrounding this pair 75 of rings is a ring 26 of larger diameter arranged

with its axis substantially coaxial with the axes of the pair of concentric rings 24 and 25. This latter ring 26, however, is positioned in a plane somewhat above the plane of the rings 24 and 25, but parallel with this latter plane. The ring 26 is secured to the outer ring 25 of the pair by means of a plurality of spaced radially positioned wires 27 which at their ends are secured in any suitable manner to the rings 25 and 26, such as by spot welding.

10 The ring 24 of the inner pair of rings is considerably smaller than the ring 25 which surrounds it, as shown in Fig. 2. Arranged between the inner pair of rings are a plurality of metallic baffles or vanes 28 arranged generally radially of the rings, as shown in Fig. 2. These baffle members 28, as shown in Fig. 2, have a curved shape and are secured at their inner and outer ends to the rings 24 and 25, respectively, at substantially uniform intervals circumferentially of the rings so as to define a plurality of circumferentially spaced compartments 30 for receiving platters, plates and like flat dishes. The members 28 are supported at an angle to the vertical. The angle at the inner ends of the members may be approximately 5° to the vertical, the angle increasing to approximately 25° at the outer ends of the members. The compartments 30, it will be observed, are arranged so as to support the dishes in a generally upright position and substantially tangentially to the inner ring 24. The baffles 28 preferably will be supported in an elevated position with reference to the plane of the rings 24 and 25 by means of vertically arranged posts 31 arranged at the inner and outer ends of the baffles and secured to the 20 baffles and to the inner and outer rings 24 and 25 respectively in any suitable manner, as by spot welding.

A suitable upright open-work circular wall is 40 provided at the outer ring 26. This wall is defined by a plurality of upright wire members 33 spaced at substantially uniform intervals circumferentially of the outer ring 26. These members 33 at their upper ends support a ring member 34 having a diameter substantially equal to the diameter of the outer ring member 26. The members 33 are secured to the rings 26 and 34 in any suitable manner, as by spot welding. Secured to the lower ends of the upright members 33 are a plurality of feet or supporting legs 35. These legs are 50 secured at their upper ends to the upright members in any suitable manner. For this purpose, the lower ends of the upright members 33 are extended somewhat below the plane of the ring 26 and these ends are provided with eyelets 33a. 55 The upper ends of the legs 35 are provided with corresponding eyelets 35a and the two eyelets are secured together by means of bolts 36. The legs are sufficiently long so that when the tray is positioned within the lower portion of the vat 10, 60 they will support the tray in an elevated position with reference to the impeller 14. Preferably, the legs 35 will support suitable rollers 37 at their lower ends, as clearly shown in Figs. 1 and 3.

The entire bottom of the tray is covered by means of a screen member 38 formed of wires woven together in mesh form, as clearly shown in Figs. 2 and 3. This screen, as shown, has a substantially circular shape to conform to the contour of the tray. The screen member is secured to the rings 24 and 25 and to the outer ring 26 in any suitable manner, as by spot welding. As shown, it is preferable to place this screen below the lower surfaces of the rings 24 and 25 and to 75

wrap its peripheral edge around the ring member 26.

It will be observed in view of the foregoing construction that the lower rack provides a plurality 5 of compartments 30 arranged radially of the rack, while a second circular or annular shaped compartment 39 is provided around the radial compartments 30. The dishes will be placed within the radial compartments 30 so as to rest against the baffles 28 with the faces or upper surfaces of the dishes facing clockwise. The dishes supported in the compartment 39 will be placed with their upper edges resting against the ring 34 and their lower edges against the posts 31. This supports 15 the plates at an angle to the vertical, and preferably they will be positioned so that their upper surfaces face the bottom of the vat.

In using the trays, it will be understood that they may be loaded or unloaded while positioned 20 within or without the vat. When it is desired to wash the dishes, the lower rack is supported in the vat upon its legs 37 and will be loaded with flat platters, plates and the like, while the upper rack 21 will be loaded with the glasses, etc.

After the racks have been loaded, the cover 12 of the vat will be closed, the drain valve closed and cleansing water supplied to the vat. The impeller will then be operated to wash the dishes.

Heretofore, the compartments of the lower rack 30 for the plates and platters were defined by open-work construction and the plates and platters themselves were in the main relied upon to deflect or direct the water from the impeller upwardly through the upper rack 21 so as to wash the dishes 35 therein. In the lower rack arranged in accordance with this invention, the baffle members 28 perform this function. Thus, the water is distributed or deflected upwardly into the upper rack 21, irrespective of whether or not the compartments 40 30 are loaded with dishes. This feature is quite important, because oftentimes it is desirable to wash merely a batch of glasses when there are a limited number or no dishes or platters at all 45 available to be washed in the lower rack.

The baffles 28 arranged in accordance with this invention will efficiently deflect or guide the water hurled by the impeller up into the dishes placed within the upper rack so as to effect an efficient washing action.

The bodies of the baffles 28, it will be observed, are directed substantially tangentially to the ring 24, while their inner ends are curved inwardly to meet the ring, as clearly shown in Fig. 2. The plates placed within the compartments formed by the baffles will be supported substantially tangentially to the ring 24. As the dishes are placed with their upper faces directed clockwise and as the impeller 14 shown is rotated in a counter-clockwise direction as viewed in Fig. 2, their soiled faces will be subjected directly to the whirling body of water projected upwardly and circumferentially by the impeller. The plates or baffles, as the case may be, however, break up the whirling body of water and deflect it directly upwardly into 5 the open vessels placed within the upper rack 21.

It is not necessary that the baffles 28 be placed in the exact position shown in Fig. 2, or that they be given the exact curved shape shown in Fig. 2. It is important, however, that the baffles be positioned so as to support the flat dishes in generally upright planes, whereby their faces will be presented more or less to the whirling fluid which is agitated by the impeller so that they will be washed efficiently. It is also desirable that the 5 vanes 28 be positioned in generally upright planes

substantially tangentially to the inner ring 24, the axis of which is coaxial with the axis of the impeller, so that the vanes are supported in general in a direction approaching the tangent to the whirling body of water agitated circumferentially 5 by the impeller. By reason of this arrangement, the blades engage the whirling mass of water to deflect it in a generally upward direction through the upper tray. If the impeller 14 were arranged to rotate in the reverse direction the blades 28 10 would be reversed.

In Figs. 4, 5 and 6, there is illustrated a form of this invention wherein the baffles are supported on a framework which does not at the same time function to support dishes. In this case the vat is 15 of square cross-section, but it may be circular. As shown in Figs. 4, 5 and 6, there are a number of baffles 40. These baffles are supported in concentrically arranged inner and outer rings 41 and 42 in substantially the same positions relative to 20 the rings as are the baffles 28 of Figs. 1 to 3 supported relatively to their rings 24 and 25. The rings 41 and 42, however, are somewhat smaller in diameter than the rings 24 and 25, and the ring 41 is in a plane elevated somewhat with respect to the plane of the ring 42, as shown in Fig. 4. The inner and outer ends of the baffles are provided with circumferentially arranged extensions 44 and 45 respectively bearing on the outer and inner surfaces of the rings 41 and 42, as shown in Figs. 30 4 and 6, and secured to these members in any suitable manner, as by welding.

The rings are supported by four wire members 46 spaced apart approximately 90° about the outer ring 42 and provided with portions 47 arranged 35 substantially normal to tangents to the ring at the points of engagement of the wires with the ring. The inner ends of the wires have reduced extensions 48 received in apertures provided for them in the ring, and are secured to the ring in 40 any suitable manner as by butt welds.

The normal portions 47 of the wires 46 merge into portions 50 that extend downwardly at an angle to the normal portions, as shown in Fig. 4, and these portions, in turn, curve into upright 45 portions 51. These portions 51 at their upper ends are turned inwardly to form horizontal portions 52 lying in the vertical planes of the portions 47 and 50, as shown in Fig. 6.

Substantially half-way up the vertical portions 50 55 is a closed square wire ring 53 secured to the inner surface of the portions 51 in any suitable manner, as by welding. And arranged at the corners of this square ring are wire reinforcing members 54. These members have an inverted U- shape and are arranged to straddle the corners of the wire 53, as shown in Fig. 6. The lower ends of these members are welded or otherwise suitably secured to the ring 53. The horizontal portions 52 of the wires 46 are supported by these 60 members 54, the latter members having depressed curved portions 55 in the bases of the U for receiving the wires 51. The wires 51 and 54 preferably will be welded together.

The framework supporting the baffles 40 is 65 completed by feet 56 secured to the wires 46 and arranged to support the framework in an elevated position in the vat, as shown in Fig. 4.

The framework just described is quite rigid and mechanically strong, and is utilized to support an upper tray, as well as the baffles 40.

The upper tray or rack has a square contour, as has the lower framework. This rack comprises a relatively small square ring 60 at the center of the rack and a considerably larger 75.

square ring 61 arranged symmetrically about the ring 60, as shown in Fig. 5, and in a plane somewhat below it, as shown in Fig. 4.

A larger square ring 62 is arranged symmetrically with and about the inner square rings 60 and 61, but in a plane somewhat above the planes of these rings, as shown in Fig. 4. The rings 60, 61 and 62 are secured together by means of wire corner stays 63 and cross stays 64 arranged at the corners of the tray, and in one central axis of the tray, respectively, as shown in Fig. 5. The wire stays have approximately an L-shape, as shown in Fig. 4, the long legs of the stays bearing under the rings 60 and 61 and extending outwardly of the tray to the short legs which extend vertically upwardly tangentially to the wire 62, as shown. The stays where they connect the wires 60, 61 and 62 will be secured to the wires in any suitable manner, as by 20 welding.

The framework of the upper tray is completed by a pair of handles 65 secured at the opposite sides of the tray, as shown in Figs. 4 and 5. The handles in side elevation have approximately an L-shape, as shown in Fig. 4, and in front elevation have a substantially U-shape. The lower ends 65a of the U-shaped handles are turned inwardly and slightly inclined upwardly where they are secured to the intermediate ring 61 30 in any suitable manner, as by welding.

The two vertical portions 65b of these handles, as shown, extend upwardly in the vertical planes of the associated sides of the wire 62 until they reach the wire and then incline inwardly somewhat toward the center of the tray, as shown in Fig. 4, and toward each other, as shown in Fig. 5. These vertical portions 65b are joined by means of horizontal portions 65c.

Supported within the framework just described 40 is a suitable tray frame assembly which comprises a pair of octagonal shaped wire rings 66 and 67, arranged one above the other and having a size just slightly smaller than the outer square ring 62, as shown in Fig. 4. The sides 45 of the octagonal rings 66 and 67 at the corners of the tray are somewhat shorter than the remaining four sides, as clearly shown in Fig. 5. The two rings 66 and 67 are secured together in vertically spaced relation, as shown in Fig. 4, by 50 means of vertical wires 68 arranged at each corner of the octagon and in the middle of the longer side members of the octagon, as clearly shown in Fig. 5. These wires are secured at their upper and lower ends to the wires 66 and 67 in any suitable manner, as by welding.

55 A wire screening member 70 is placed over the entire bottom of the upper tray. This member 70, as shown, rests upon the upper surfaces of the rings 60 and 61 and extends under the lower octagonal ring 66 and thence upwardly in the vertical planes of the rings 66 and 67 to the upper ring 67, where the edges of the screen are bent over and around the upper horizontal ring 67, as shown in Fig. 4. It will be observed that 60 this arrangement of the screening member 70 provides a bottom wall for the upper tray tapering downwardly from the center of the tray to its eight vertical side walls.

70 Arranged substantially in the central portion of the tray is a suitable soap or detergent container 71. This container comprises a cylindrical body portion 72 over the mouth or lower end of which is positioned a closure member 73. This closure member, as shown, is secured in spaced 75 relation with the lower edge of the cylinder 72

by means of legs 74 attached to the lower edge of the container 72 and directed through apertures 75 provided for them in the closure member. The legs are turned inwardly, as shown, and are secured to the closure member. Arranged above the closure member is a conical member 76 arranged in an inverted position, as shown in Fig. 7, and secured to the closure member by means of a flange 77 attached to the cone. This flange is provided with apertures receiving the 10 legs 74. The upper end 78 of the cylinder is flared outwardly and terminates in upright walls 79 which form a square, open at the corners. It will be understood that a suitable detergent will be placed within the cylinder 72 on the conical 15 wall 76 and that when the impeller 80 is operated, some of the water hurled upwardly through the vat will gravitate into the cylinder 72 through its upper open end and will wash detergent from the cylinder through the space between its bottom and the closure member 73.

While the baffles 40 of the lower open framework may have any suitable shape, it is important that they be given a shape such that the water which is hurled circumferentially and upwardly by the impeller 80 be engaged by the baffles so as to be directed upwardly and outwardly and distributed substantially uniformly over the bottom of the wire screening 70 upon which the vessels in the upper tray are placed. In the particular form shown, there are twelve baffles spaced substantially 30° apart. Preferably, the outer ends of the baffles will be advanced with respect to the inner ends of the baffles in a clockwise direction by an angle of approximately 52°. In other words, the outer end of each baffle indicated by the letter A (Fig. 6) will be in advance of the inner end of the baffles indicated by the letter B, by an angle of 52°. The blades will also be inclined upwardly from their lower edges so that their faces incline forwardly in a counterclockwise direction, as viewed in Figs. 4 and 6. The inclination of the blades and the curvature, of course, depends upon the direction of rotation of the impeller 80 which, as viewed in Fig. 4, is 45 in the counterclockwise direction. If the impeller were arranged to rotate in the reverse direction, the arrangement of the blades 40 would be reversed.

In the operation of the washing apparatus of 50 Figs. 4, 5, and 6, it will be understood that the lower frame will be placed in the lower portion of the vat and the upper tray will be placed upon the lower tray so that it rests upon and is supported by the U-shaped members 54, and the 55 horizontal portions 52 of the wire members 46. Then the upper tray will be loaded with the glassware, cups and the like with their basins facing downwardly in the vat. When the impeller 80 is 60 operated it will circulate the water upwardly and outwardly circumferentially through the vat, the whirling mass of water striking the vanes or baffles 40 so that the water is deflected upwardly and outwardly and distributed substantially uniformly over the screening 70.

The form of my invention disclosed in Figs. 4-6 is described and claimed in my above-mentioned copending divisional application, Serial No. 193,909.

70 While I have shown particular embodiments of my invention, it will be understood, of course, that I do not wish to be limited thereto since many modifications may be made, and I, therefore, contemplate by the appended claims to cover any 75

such modifications as fall within the true spirit and scope of my invention.

What I claim as new and desire to secure by Letters Patent of the United States, is:

5. 1. Dishwashing apparatus comprising a vat, a rotatable impeller in the lower portion of said vat and in its central axis arranged to hurl cleansing liquid upwardly and outwardly in the vat, an open-work dish-supporting tray in the 10 vat above said impeller so that the liquid hurled by the impeller is directed upwardly and outwardly through the tray, a plurality of fixed baffles within said tray arranged generally vertically and positioned in the tray to provide a plurality 15 of circumferentially arranged compartments in the tray for receiving dishes and the like, the compartments being arranged substantially symmetrically to the central axis of the vat, and the baffles functioning to support the dishes and also 20 positioned with respect to the impeller to deflect the liquid hurled upwardly by the impeller to direct it upwardly in the vat in predetermined directions, and means supporting the tray in the vat so that the tray and the baffles supported in 25 it do not move under the impact of the liquid on the baffles.

2. In combination with dish-washing apparatus having a vat, a power-driven liquid circulating impeller within the lower portion of said vat arranged to engage cleansing liquid and hurl it 30 upwardly and outwardly circumferentially with a whirling motion in said vat and a pair of superimposed open-work dish-supporting trays in said vat above said impeller, the open-work tray 35 constituting the lower of said trays comprising a closed wire member, an open-work bottom wall for said tray attached to said member, a second smaller closed wire member within said first wire member attached to said bottom wall, and a plurality 40 of spaced metallic baffle members having their ends attached to said pair of closed wire members respectively, said baffle members supported by said closed wire members in a generally vertical position so as to define a plurality of 45 compartments for receiving dishes and the like and so as to present surfaces in the path of the cleansing liquid hurled upwardly by said impeller to direct said liquid in predetermined directions upwardly through the rack above it.

3. A dishwashing apparatus comprising a vat 50 and an impeller in the lower portion of said vat arranged to hurl cleansing fluid upwardly and outwardly in said vat, an open-work dish-supporting tray in said vat comprising a pair of 55 concentric rings lying substantially in the same plane, a ring of larger diameter having its axis coincident with the axes of said pair of rings but lying in a plane elevated with respect to the plane of said pair of rings, means rigidly connecting said outermost ring to the outer of said 60 pair of rings, an open-work mesh bottom member secured to said rings, wire members defining an upright marginal wall at the outermost ring, a plurality of metallic upright baffles arranged 65 generally radially of said inner rings, means securing the ends of said baffles to said pair of rings so as to support said baffles at an angle to the vertical, thereby defining compartments for receiving plates, flat dishes and the like and 70 supporting said dishes at an angle to the vertical in a position substantially tangentially to the

inner one of said pair of rings, and further, to function as vanes to deflect fluid agitated by said impeller in predetermined directions upwardly in said vat.

4. Dishwashing apparatus comprising a vat, an 5 impeller in said vat rotatable for circulating cleansing liquid upwardly in said vat, an open-work utensil supporting rack in the upper portion of said vat above said impeller, an open-work supporting means in said vat between said 10 rack and impeller through which liquid from said impeller is directed, a plurality of baffles on said supporting means arranged generally radially with respect to the central vertical axis of said 15 vat and having liquid engaging surfaces arranged generally vertically with the inner ends of said baffles inclined to the vertical at a smaller angle than the outer ends, and means securing said baffles to said supporting means.

5. Dishwashing apparatus comprising a vat, a 20 liquid circulating impeller rotatable in said vat, an open-work dish-supporting rack in said vat above said impeller, a pair of substantially concentric rings above said impeller and below said 25 rack, a plurality of metallic baffles provided with liquid-engaging faces spaced at intervals circumferentially of the rings and extending generally radially of said rings, and means connecting said 30 baffles to said rings so as to support them in an upright position at an angle to the vertical with the inner ends of said baffles inclined at a smaller angle to the vertical than the outer ends.

6. Dishwashing apparatus comprising a vat, a liquid circulating impeller rotatable in said vat, an openwork dish-supporting rack in said vat 35 above said impeller, a pair of substantially concentric rings above said impeller and below said rack, a plurality of metallic baffles provided with liquid-engaging faces spaced at intervals circumferentially of the rings and extending generally 40 radially of said rings, and means connecting said baffles to said rings so as to support them in an upright position at an angle to the vertical with the inner end of said baffles inclined at a smaller 45 angle to the vertical than the outer ends and the baffles curving in the direction of rotation of said impeller.

7. Dishwashing apparatus comprising a vat, a rotatable impeller in said vat for circulating cleansing liquid in the vat, a supporting member 50 within the vat, and a plurality of baffles on said supporting member arranged generally radially to the central vertical axis of the vat and arranged generally vertically in said vat with the inner ends of the baffles inclined at a smaller 55 angle to the vertical than the outer ends and the baffles curving in the direction of rotation of the impeller.

8. Dishwashing apparatus comprising a vat, a rotatable impeller in said vat for circulating 60 cleansing liquid in the vat, a supporting member within the vat, and a plurality of baffles on said supporting member arranged generally radially to the central vertical axis of the vat and arranged generally vertically in said vat with the 65 inner ends of the baffles inclined at an angle of approximately 5° to the vertical and the outer ends at an angle of approximately 25° to the vertical.
